C. E. KOHLMANN,
 DEVICE FOR FASTENING ELECTRIC LIGHT BULBS TO A SOCKET.
 APPLICATION FILED MAY 20, 1915.
1,169,497. Patented Jan. 25, 1916.

UNITED STATES PATENT OFFICE.

CLARENCE E. KOHLMANN, OF FRESNO, CALIFORNIA.

DEVICE FOR FASTENING ELECTRIC-LIGHT BULBS TO A SOCKET.

1,169,497.

Specification of Letters Patent.

Patented Jan. 25, 1916.

Application filed May 20, 1915. Serial No. 29,430.

To all whom it may concern:

Be it known that I, CLARENCE E. KOHLMANN, a citizen of the United States, and a resident of the city of Fresno, county of Fresno, and State of California, have invented a new and useful Device for Fastening Electric-Light Bulbs to a Socket, of which the following is a specification.

It is known that heretofore sockets for electric light bulbs have been constructed so the bulbs can be screwed therein, and which have catches arranged to prevent the bulbs from being readily unscrewed but these prior inventions require a screw and socket of special construction.

The object of my invention is to form an auxiliary attachment which can readily be attached on an ordinary screw bulb socket now in general use which auxiliary device will permit the bulb to be screwed in the regular socket, and when therein such auxiliary device will keep the bulb from being unscrewed unless a key of special design is used to unlock the catch therein, that such auxiliary device can be easily removed by the person having the key, and that it can be cheaply constructed.

In the drawing which accompanies this specification, Figure 1 shows the auxiliary attachment fastened to an ordinary screw lamp socket, with the electric light bulb fastened therein. Fig. 2 is a part sectional view of the auxiliary device through line *z* on Fig. 3. Fig. 3 is a sectional view of the device through sectional line *x* shown in Fig. 2. Fig. 4 is a key for unlocking said auxiliary device.

B is a frame or box containing the locking device and consists of bottom 2, a top 3 and a side 4.

D is a member securely fastened to and between top 3 and bottom 2. Member *D*, top 3, bottom 2 have a hole *C* directly through them of such dimension that the screw end of the electric bulb can readily pass through. In the inner wall of member *D* I have cut a plurality of recesses 5, 6, 7 and 8 of approximately the shape shown in the drawing, such recesses being deeper at the one end than the other. The outer wall of member *D* is approximately circular.

E is a movable collar surrounding member *D*. Collar *E* has a handle 9 extending through wall 4. The opening in wall 4 through which handle 9 extends is of suffi-

cient size to permit the collar *E* to be moved around member *D* within defined limits.

5^a, 6^a, 7^a and 8^a are holes through member *D* forming openings from the deeper ends of recesses 5, 6, 7 and 8 to the outside of said member *D*.

F is a catch which consists of a roller 10, a wire 11 and a spring 12. Wire 11 has roller 10 attached to one end and is slidably pivoted at the other end to a point on collar *E* so that such wire 11 can slide within opening 6^a when collar *E* is moved. The relation of recess 4 and collar *E* is such that collar *E* can be turned in one direction sufficiently to draw roller 10 to the larger end of the recess 5, 6, 7 or 8.

12 is shown in the drawing to be a circular compression spring and encircles wire 11 and engages shoulder 13 in the recess 6.

The relation of recess 6, roller 10, spring 12, wire 11 and collar *E* is such that when collar *E* is moved in one direction roller 10 will be drawn into the deeper end of recess 6, and between the inside and outside walls of member *D* and when collar *E* is turned in the other direction a segment of roller 10 extends slightly beyond the limits of the inner wall of member *D*. Rollers 10 are normally protruding beyond the inside wall of member *D* as the spring 13 presses such balls toward the smaller end of recesses 5, 6, 7 or 8.

G is a catch for locking collar *E*. It consists of a slide 26 and an engaging recess 25 in the outer wall of collar *E*. By means of spring 27 slide 26 is normally held in engagement with recess 25, and by means of a key, slide 26 can be released from such engagement and collar *E* can be moved. To attach this auxiliary lock to the lamp socket *L* I have attached a collar *K* to box *B*. This collar is constructed to encircle the lower end of socket *L* and by means of a set screw 30 it is clamped thereto. To further secure such auxiliary lock I have attached a strap 100 preferably of metal to one side of the box, pass it over the top of socket *L* and between the wires, and through an opening *H'* on the opposite side of the box. Strap *H* is provided with a plurality of holes 33, and box *B* has a slide 31 therein passing through a hole which intersects hole *H'*. Slide 31 has the end thereof cut obliquely as an ordinary door lock so in pulling the strap through it will tighten easily but when the

strap is pulled backward it will lock. By drawing the end of strap H through hole H¹ it can be locked therein by passing slide 31 through either of holes 33.

5 32 is a spring intended to hold slide 31 in a position intersecting hole H¹.

The end of slide 31 is beveled so strap H can be readily pulled downwardly but in pulling the strap the other way it will 10 interlock.

It will be noted that when this device is attached to socket L, a lamp fitting such socket will pass through hole C and can be screwed into the socket as the rollers 10 will 15 readily retreat into the larger end of recesses 5, 6, 7, and 8, but in attempting to unscrew the bulb rollers 10 will be forced toward the smaller end of such recess and thereby cramp and lock the bulb to box B.

20 I claim as my invention and desire Letters Patent upon:

1. The combination of an inclosed box having a circular hole therein, a ring member within and attached to such box with 25 the hole in such member registering with the hole in such box, having elongated recesses in the inner walls of such ring with the depth at one end greater than the depth at the other end and a hole through such 30 ring member connecting with the large end of such recess, a roller fitted into such recess, such roller being of such diameter that when it is within the larger end of such recess it is between the inner wall and outer 35 wall of such ring member and as it is moved toward the smaller end of such recess a section thereof extends beyond the inner wall of such ring, a collar normally free to rotate around such ring member, a wire pivoted to 40 the roller at one end and slidably pivoted to the collar at the other end, means for limiting the rotation of such collar means for locking such collar so it cannot rotate, means for connecting such box to an electric 45 light socket, all substantially as described.

2. In combination, an electric light socket, an electric light bulb, screw threads on such socket and bulb constructed to coöperate, an auxiliary member consisting of an 50 inclosed box, a ring within such box and attached thereto, such ring having an inside diameter to permit free access of the screw portion of such bulb, a hole through the top and bottom of such box registering with the hole 55 in the ring, a collar constructed to fit around the outside of the lower portion of such socket and attached to such box so the hole in the ring will register with the screw hole in such socket, means for attaching 60 such collar to the socket, a plurality of rollers, a plurality of elongated recesses in the inner wall of such ring of uniformly increasing depth, the depth at the deepest end being not less than the diameter of such 65 rollers, and the width of such recess being the

length of such roller, a collar normally free to rotate around said ring, holes from the larger ends of such recesses through the outside walls of such ring, wires slidably fitted within such holes slidably pivoted at one end to such collar, and pivoted at the other end to such rollers, means for holding such rollers normally in a position so an arc thereof is outside of the inside wall of such ring, means for locking such collar to such box, all substantially as described.

3. In combination, an electric light socket, an electric light bulb, screw threads on such socket and bulb constructed to coöperate, an auxiliary member consisting of an inclosed box, a ring within such box and attached thereto, such ring having an inside diameter to permit free access of the screw portion of such bulb, a hole through the top and bottom of such box registering with the hole in the ring, a collar constructed to fit around the outside of the lower portion of such socket and attached to such box so the hole in the ring will register with the screw hole in such socket, a strap attached to one side of the box, which is passed over the top of the socket and through a hole in such box, and means for locking such strap within such hole, a plurality of rollers, a plurality of elongated recesses in the inner wall of such ring of uniformly increasing depth, the depth at the deepest end being not less than the diameter of such rollers, and the width of such recesses being the length of such roller, a collar normally free to rotate around said ring, holes from the larger ends of such recesses through the outside walls of such ring, wires slidably fitted within such holes, slidably pivoted at one end to such collar and pivoted at the other end to such rollers, means for holding such rollers normally in a position so an arc thereof is outside of the inside wall of such ring, means for locking such collar to such box, all substantially as described.

4. In combination, an electric light socket, an electric light bulb, screw threads on such socket and bulb constructed to coöperate, an auxiliary member consisting of an inclosed box, a ring within such box and attached thereto such ring having an inside diameter to permit free access of the screw portion of such bulb, a hole through the top and bottom of such box registering with the hole in the ring, a collar constructed to fit around the outside of the lower portion of such socket and attached to such box so the hole in the ring will register with the screw hole in such socket, means for attaching such collar to the socket a plurality of rollers, a plurality of elongated recesses in the inner wall of such ring of uniformly increasing depth, the depth at the deepest end being not less than the diameter of such rollers, and the width of such recess being the

- length of such roller, a collar normally free to rotate around said ring, holes from the larger ends of such recesses through the outside walls of such ring, wires slidingly fitted 5 within such holes, slidingly pivoted at one end to such collar, and pivoted at the other end to such rollers, means for holding such rollers normally in a position so an arc thereof is outside of the inside wall of such 10 ring, means for locking such collar to such box consisting of an indent in the outside wall of such collar, a sliding member nor- mally held in engagement with such indent, a keyhole through such box, and an independent key constructed to enter such key-hole and release such sliding member from such recess and means for moving such collar in a position to hold such rollers in the deepest portion of such recesses, all substantially as described. 15

CLARENCE E. KOHLMANN.
